UNITED STATES PATENT OFFICE.

WILLIAM A. GEIGER, OF CHICAGO, ILLINOIS, ASSIGNOR TO WILLIAM H. MINER, OF CHAZY, NEW YORK.

MEANS FOR CONNECTING YOKE-STRAPS TO DRAW-BARS FOR RAILWAY-CARS.

1,286,278.

Specification of Letters Patent. Patented Dec. 3, 1918.

Application filed June 9, 1917. Serial No. 173,843.

To all whom it may concern:

Be it known that I, WILLIAM A. GEIGER, a citizen of the United States, residing at Chicago, in the county of Cook and State of Illinois, have invented a certain new and useful Improvement in Means for Connecting Yoke-Straps to Draw-Bars for Railway-Cars, of which the following is a full, clear, concise, and exact description, reference being had to the accompanying drawings forming a part of this specification.

My invention relates to improvements in means for connecting yoke straps to draw-bars for railway cars.

The object of my invention is to provide a simple and efficient means for connecting a yoke-strap to a draw-bar.

In the drawings forming a part of this specification, Figure 1 is a side elevation, partly in vertical longitudinal section, of a draw-bar and yoke-strap with my improved connecting means applied; Fig. 2 is a front end view of the structure; and Fig. 3 is a perspective view of one of the retaining clevises.

Referring to the drawings, the numeral 10 indicates a yoke-strap of usual construction, having an upper limb 11, a lower limb 12, a rear connecting member 13, and upper and lower in-turned gibs 14 and 15, respectively, provided at the forward free ends of the strap. 16 refers to a draw-bar of the usual type having a shank 160 and a butt 17, the butt being provided with upper and lower shoulders 18 and 19, respectively, adapted to be engaged by the upper and lower gibs, respectively, of the yoke-strap. The draw-bar is also provided with the usual spaced apart vertical rivet holes 20-20, and the yoke strap is provided in its upper limb with the usual rivet holes 21-21, and in the lower limb with the rivet holes 22-22 registering, when the yoke and draw-bar are assembled, with the rivet holes 40 in the draw-bar. Instead of employing rivets to secure the draw-bar and yoke-strap together, I employ a readily detachable connecting means which comprises an upper clevis 23 and a lower clevis 24. Each of said clevises is a U-shaped member having the transverse connecting web 25 and the spaced apart vertical legs 26-26. One of said clevises passes around one limb of the yoke

and straddles the draw-bar,--the other leg passes about the other limb of the yoke and 55 likewise straddles the draw-bar, the legs of said clevises being suitably overlapped and being provided in their overlapping portions with the transverse perforations 27-27 which register with each other and with the 60 usual transverse coupler key slot 28. A coupler key 29 passes through both clevises and the draw-bar, and serves to hold the clevises in their assembled position upon the draw-bar and yoke, as well as to form a 65 connection between the clevises and the draw-bar. A further connection between the clevises and draw-bar, between the draw-bar and yoke-strap, and between the clevises and the yoke-strap is found in the integral 70 pins 30-30 with which the inner face of each transverse member 25 of the clevises is provided, the said pins being adapted to pass through the usual rivet holes in the adjacent limb of the yoke-strap and to enter 75 the adjacent portions of the usual rivet holes provided in the draw-bar.

In assembling the parts, the yoke-strap is placed upon the draw-bar, the upper and lower clevises are then placed in their positions with the pins entering rivet holes in the yoke-strap and draw-bar, as hereinbefore described, and the coupler key 29 is then inserted in its position.

It will be noted that upon pull of the 85 draw-bar the strain of the connection between the draw-bar and yoke-strap is upon the coupler key 29 and the clevises which are secured to the yoke-strap, and also upon the pins which directly connect the yoke-strap 90 to the coupler, so that the pins 30 are under double shear. A firm and readily detachable connection between the draw-bar and yoke-strap is thus provided, as well as one in 95 which the strains, either in pulling or buffing movement of the parts, is well distributed.

I claim:

As an article of manufacture, a detachable 100 connection for draw bars and yokes of railway draft riggings having the usual aligned upper and lower sets of rivet receiving holes, said connection comprising two clevises, each of said clevises being provided on the inner face of the transverse portion thereof with a 105 pair of integral, relatively short pins adapted

to be extended through the adjacent upper or lower set of alined rivet receiving holes of the draw bar and yoke, said clevises having the side arms thereof arranged to overlap 5 when in assembled position, the overlapped portions of said side arms being provided with alined slots adapted to receive a coupler

key whereby the pins when the parts are in operative position, are placed under double shear.

10

In witness that I claim the foregoing I have hereunto subscribed my name this 21st day of May, 1917.

WILLIAM A. GEIGER.
